UNITED STATES PATENT OFFICE

FREDERICK RICHARD SHAW, OF ARMSTRONG, BRITISH COLUMBIA, CANADA

RADIO LOUD-SPEAKER

Application filed March 21, 1928. Serial No. 263,578.

This invention relates to improvements in loud speakers for use with radio receiving sets and the like. Its primary object being to amplify the signal received in the telephone 5 piece. It is designed to be used with a pair of standard head-phones. The head-phones being placed on the receptacles for same on the loud speaker and the amplified signal will proceed from the horn. A further object be- 10 ing to get the same volume of sound with a reduced number of radio tubes, thereby making a receiving set more economical to construct and operate. Another object being to provide a loud speaker for operation in com- 15 junction with a "crystal set" and a pair of high resistance head-phones. With this combination no batteries being necessary thus providing a very cheap receiving set.

With these and other objects in view as 20 will appear as the description proceeds the invention consists in the novel construction and arrangement of parts as hereinafter more specifically set forth claimed and shown in the accompanying drawings forming a part 25 of this present application and in which:

Fig. 1 is a view of the improved loud speaker.

Fig. 2 is a sectional view through the amplifier.

Fig. 3 is a part sectional view of same 30 along line A. A. of Fig. 2.

Referring more in detail to the drawings in which similar reference characters designate corresponding parts throughout the several 35 views it will be seen the improved loud speaker comprises a horn 10 of the usual type which is fitted into a horizontal tone arm 11 supported upon a base 12 of substantial heavy 40 design to give stability to the speaker. Each end of the tone arm is enlarged to the shape shown at 13 into which are fitted the cylinder shells 14 and are secured thereto by spring 45 clips 15. 16 is a mica diaphragm being supported by an inner ring 17 and an outer ring 18, said inner ring 17 being slightly larger in cross sectioned diameter than the outer ring 18, this gives the diaphragm 16 a slightly convex shape. Secured to the center of the dia- 50 phragm 16 is a conical shaped member 19 being made preferably of carbon granules or

some graphite composition substitute and having a brass stem 20 through its center one end of which is threaded and passed through the diaphragm 16 and secured thereto by a nut 21. The function of the cone-shaped 55 member 19 is to transmit the sound impulses, emitted from the diaphragm of the head-phones, to the diaphragm 16 of the loud speaker.

The impulses of the sound potential actuate resistance vibrations in the carbon granules, similar to an electric impulse, these resistance vibrations varying according to the intensity of the sound wave pressure on the carbon granules. In turn, these resistance 60 vibrations, as registered on the carbon granules, are actuated through the medium of the brass stem 20, to the diaphragm of the loud speaker, and the resultant audibility effected 65 in the horn of the loud speaker. A rubber gasket 22 is provided to form a cushion between the shell 14 and the diaphragm 16 the spring clips 15 providing the required tension on said gasket and diaphragm. Inside 70 the shell 14 is a funnel shaped member 23 preferably of celluloid secured at its outer edge to the shell. Fitted into the enlarged end of the shell and secured thereto is a semi- 75 flexible rubber flange 24 having an inwardly disposed central hole 25. The face of said 80 flange being convex in form to fit the ear- phone pieces which are to be placed therein and on account of its flexibility will allow them to fit snug into the enlarged end or receptacle of the shell 14.

It will be seen from the foregoing that the 85 loud speaker is controlled from the head-phones placed into the receptacles for the same, and that the diaphragm of the loud speaker is actuated by the movement of the diaphragm of the phone piece.

It is believed that the construction and advantages of the structure shown may be apparent from the foregoing paragraphs taken in conjunction with the accompanying drawings without further detailed description.

While the preferred embodiment of the invention has been disclosed it is understood that minor changes in the details of construction, combination and arrangement of co- 100

operating elements may be resorted to within the scope of what is claimed without departing from the spirit of the invention.

What I claim is:—

- 5 1. In a radio loud speaker having a horn, a base, a horizontal tone arm connecting with said horn having enlargements at each end, a shell adapted to fit said enlargement forming an earphone piece receptacle, spring clips to secure the shell in position and a diaphragm yieldably supported in the enlarged end of the tone arm.
- 10 2. In a radio loud speaker having a horn, a base, a horizontal tone arm connecting with said horn having an enlargement at each end, a shell adapted to fit said enlargement forming an earphone piece receptacle, spring clips to secure the shell in position, a diaphragm yieldably supported in the enlarged end of the tone arm, a cone-shaped member made up of carbon granules re-inforced with a metal stem and means for securing said cone-shaped member to said diaphragm.
- 15 3. In a radio loud speaker having a horn, a base, a horizontal tone arm connecting with said horn having an enlargement at each end, a shell adapted to fit said enlargement forming an earphone piece receptacle, spring clips to secure said shell in position, and a semi-
- 20 flexible rubber flange mounted inside said shell, said flange being convex on its outer side and designed to conform itself to the shape of earphone pieces.

In testimony whereof I affix my signature,

35 FREDERICK RICHARD SHAW.
